(57) **CLAIM**

The ornamental design for a suitcase, as shown and described.

DESCRIPTION

FIG. 1 is a front perspective view of a suitcase showing my present design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The claimed design is indicated by the relatively dark portions in the figures, while the relatively light portions are environmental and form no part of the claimed design, and the representations of the design are in greyscale; the design does not claim protection for a specific coloring.
